UNITED STATES PATENT OFFICE.

LEAVETT E. CROSIER, OF HADLEY, MASSACHUSETTS.

HANDLE-GRIP FOR GOLF-STICKS, FISHING-RODS, &c.

SPECIFICATION forming part of Letters Patent No. 621,993, dated March 28, 1899.

Application filed November 1, 1898. Serial No. 695,149. (No model.)

To all whom it may concern:

Be it known that I, LEAVETT E. CROSIER, a citizen of the United States of America, residing at Hadley, in the county of Hampshire and State of Massachusetts, have invented new and useful Improvements in Cushioned Handle-Grips for Golf-Sticks, Fishing-Rods, and Like Articles, of which the following is a specification.

10 This invention relates to the construction of grips for hand-grasped implements—such as golf-sticks, fishing-rods, and like articles—the object of the invention being to produce a cushioned and waterproof grip for such articles whereby they will be less fatiguing to the hand of the user and adapted to be wet without liability of damage to the parts lying within the boundaries of said grip; and the invention consists in the construction herein-
20 after described, and clearly pointed out in the claims.

In the drawings forming part of this specification, Figure 1 shows in longitudinal section a grip embodying my improvements. Fig. 2 is a transverse section thereof on line 3 3, Fig. 1.

In carrying my invention into effect that part of the grip of an implement A to be cushioned and waterproofed may be fashioned to best adapt it to the use to which it is to be put—as, for example, the butt-end of a fishing-rod would have the enlargement B, (shown in Fig. 1,) whereas the grip part of other implements might be of some form differing from that shown; but whatever the form of the grip portion the construction of the cushioned covering therefor is the same, viz: Said grip portion of the implement is first covered by a layer of cushioning material 8, of felt or other suitable substance, which may or may not be, but preferably is, attached to the said grip portion by cementing it thereto or by winding a cord about it.

In the drawings a layer of felted material is shown made from a flat piece of suitable shape and fitted around said grip, the edges of said felt abutting against each other along a central longitudinal line; but said grip may be covered by said felt or other material in any one of a number of other ways, as by the use of a strip thereof spirally wound around the grip. What the cushioning material is or

how it is applied to the spring-grip is unessential, provided it possesses the requisite yielding equality; but I have above indicated 55 the preferable cushioning material and the preferable way of applying it to the grip. This cushion may be of such thickness as will offer to compression by the hand whatever amount of resistance may be thought most desirable. 60 After applying said cushioning material to the said grip portion a waterproof covering 10 is drawn over the said cushioning material, the extremities of said covering 10 overlapping the extremities of said cushioning material to such 65 an extent that when said covering is secured to the handle of the implement the cushioning material 8 will be completely inclosed thereby and the ingress of any water to the interior of the covering 10 be prevented. The extremities 70 of said waterproof covering may be either cemented to the handle of the implement or secured thereto by winding a cord 9 tightly thereabout, or by both cementing and winding. The latter is the preferable method. 75 After the ends of the covering 10 have been secured, as stated, whereby the interior of said covering is hermetically sealed, ferrules, as 12 and 13, may be fitted over the extremities of said covering in any convenient manner, as shown in the drawings. The application of such ferrules, however, is for their decorative effect and the further purpose they serve of protecting the ends of the covering 10 and the cord 9, wound about said 85 ends, from abrasion; but said ferrules may be omitted, if desired.

Where the waterproof covering 10 is to be used on the grip of a fishing-rod, as shown, it is preferably molded to conform substantially in contour to the part it incloses; but for grips that are substantially of the same diameter throughout their length said covering may be in the form of cylindrical tubing.

I claim—

1. A grip for golf-sticks, fishing-rods, and analogous implements comprising a solid core forming part of the handle of said implement, a layer of resilient material wound around said core, a waterproof covering for said material drawn over it and entirely inclosing it, means for securing the extremities of said covering to the surface of the implement by cementing said extremities thereto, whereby

95

100

water is excluded from the interior of said covering and the grip is secured in position on said implement, substantially as described.

2. A grip for golf-sticks, fishing-rods, and 5 analogous implements comprising a solid core forming part of the handle of said implement, and a yielding and waterproof surface applied to said core consisting of a layer of resilient material wrapped around said core, and a rubber sleeve drawn over said resilient material, 10 the ends of which sleeve extend beyond the ends of said material and are tightly sealed to the surface of said implement to exclude water from the interior of said sleeve, substantially as described.

LEAVETT E. CROSIER.
